WINDOW VENTILATOR

Filed Jan. 29, 1931

INVENTOR

Wesley T. Crouse.

By Ralph Koenig
ATTORNEY

UNITED STATES PATENT OFFICE

WESLEY T. CROUSE, OF ST. LOUIS, MISSOURI

WINDOW VENTILATOR

Application filed January 29, 1931. Serial No. 512,020.

This invention relates to a certain new and useful improvement in window-ventilators and has for its chief object the provision of a sectional window-ventilator of simple and inexpensive structure, which may be easily operatively installed, which is conveniently adjustable for use with windows of different sizes, and which is efficient in the performance of its intended functions.

10 And with the above and other objects in view, my invention resides in the novel features of form, construction, arrangement, and combination of parts hereinafter described and pointed out in the claims.

15 In the accompanying drawing,

Figure 1 is an elevational view of a standard window and its frame equipped with a ventilator embodying my invention;

20 Figure 2 is an enlarged vertical sectional view through the window, frame, and ventilator, taken approximately on the line 2—2, Figure 1; and

25 Figure 3 is a transverse sectional view of the ventilator, taken approximately on the line 3—3, Figure 2.

Referring now more in detail and by reference characters to the drawing, which illustrates a preferred embodiment of my invention, A designates a standard window-frame, and B designates a standard double-sash window mounted, as is customary, in the frame A.

30 Suitably fixed flatwise upon the inner face of the opposite side-members 1 and adjacent to the sill 2 of the frame A, are plate-sections 3 suitably formed or provided at or adjacent to their outer margins with supports preferably in the form of opposed open-top slide-ways C for the ventilator D, which latter includes a 35 pair of substantially similar separate oblong-rectangular sections 4, 4', constructed preferably of glass or other suitable rigid material.

The ventilator-sections 4, 4', are disposed 40 lengthwise in overlapping relation, and adhesively or otherwise permanently fixed to, and extending lengthwise along the respective inner ends of, the sections 4, 4', are strips 5, 5', respectively, each substantially 45 of U-shape in section, as best seen in Figure 3.

Formed preferably integrally with the inner leg, and at the opposite ends, of the strip 5, are oppositely disposed extensions or tongues 6, which are bent over and loosely engaged with the contiguous section 4. 55 Similarly formed integrally with the inner leg, and at the opposite ends, of the strip 5' are oppositely disposed extensions or tongues 7, which are likewise bent over and engaged with the contiguous section 4. Thus, 60 in a simple, efficient manner, the sections 4, 4', are retained in lengthwise overlapping relation, the pairs of opposed bent tongues 6 and 7, at the same time, forming slide-ways, whereby the sections 4, 4', may be slidably shifted with relation one to the other and the ventilator accordingly conveniently adjusted in length for insertion in the supporting slide-ways C, which, as best seen in Figure 2, are preferably inclined upwardly 70 and inwardly from the sill 2, so that any air entering through the opening 8 provided on raising the lower sash of the window 3, may be directed inwardly and upwardly into the room or other enclosure by the interposed 75 ventilator D.

The ventilator is exceedingly simple in structure, may be cheaply and economically constructed, may be readily adjusted in length to meet the requirements of the particular installation, and is exceedingly efficient in the performance of its functions.

It is to be understood that changes and modifications in the form, construction, arrangement, and combination of the several 85 parts of the ventilator may be made and substituted for those herein shown and described without departing from the nature and principle of my invention.

Having thus described my invention, what 90 I claim and desire to secure by Letters Patent is,

1. A window ventilator comprising a pair of rigid companion oblong rectangular sections disposed in lengthwise overlapping relation, strips U-shaped in section permanently fixed lengthwise upon the respective transverse inner ends of said sections, and extensions on the inner leg of the respective strips bent over in opposed relation upon 100

the opposite outer faces of said sections in the formation of slide-ways engaging the respective sections upon their longitudinal margins for securing the sections together 5 in lengthwise overlapping shiftable relation.

2. A window ventilator comprising a pair of rigid companion oblong rectangular sections disposed in lengthwise overlapping relation, strips U-shaped in section permanently fixed upon and extending throughout the length of the respective transverse inner ends of said sections, and tongues on the inner leg and at the opposite ends of the respective strips bent over and upon the opposite outer 10 faces of said sections in the formation of opposed hooks engaging the respective sections upon their longitudinal margins for both securing said sections together and providing slide-ways for the lengthwise shiftable adjustment of said sections with relation one 15 to the other.

In testimony whereof, I have signed my name to this specification.

WESLEY T. CROUSE.
